United States Patent Office

Des. 219,445
Patented Dec. 15, 1970

219,445

FISHING PLUG

George E. Ross, St. Paul, Minn., assignor of one-half to Frances R. Drake, Minnetonka, Minn.

Filed Dec. 29, 1969, Ser. No. 20,692

Term of patent 14 years

Int. Cl. D22—07

U.S. Cl. D22—27

FIG. 1 is a top view of a fishing plug embodying my new design;

FIG. 2 is a right side elevation view of the fishing plug; the left side elevation view being a mirror image of the same;

FIG. 3 is a bottom view of the same;

FIG. 4 is a front elevation view of the same; and

FIG. 5 is a rear elevation view of the same.

I claim:

The ornamental design for a fishing plug, as shown and described.
